UNITED STATES PATENT OFFICE.

CHRIST PAPOUCHIS, OF FAR ROCKAWAY, NEW YORK.

GAME APPARATUS.

Application filed May 31, 1922. Serial No. 564,685.

To all whom it may concern:

Be it known that I, CHRIST PAPOUCHIS, a citizen of the United States, residing at 306 Central Avenue, Far Rockaway, New York, have invented certain new and useful Improvements in Game Apparatus, of which the following is a specification, reference being had to the accompanying drawings, forming a part hereof.

This invention relates to game apparatus in which the balls are bowled or rolled at a target, and are returned automatically to the player's end of the alley. The invention is concerned particularly with the devices by which the apparatus is made self-scoring, the delivery of each ball at one point or another of the target effecting the advance of an indicator and register by an extent which corresponds to the relative value of the point of the target at which the ball is delivered. The invention is also concerned with the means for resetting the register at the end of a string of balls and for the release of a determinate number of balls, such resetting and release mechanisms preferably being coin-controlled. The apparatus in its complete form can therefore be set up in a public place of amusement and used without requiring the services of a special attendant. The several features of improvement will be referred to in detail hereinafter, with reference to the accompanying drawings in which they are illustrated as embodied in a suitable and convenient form of apparatus. In the drawings—

Figure 1 is a view of the complete game apparatus in side elevation, the target and registering apparatus being indicated by broken lines.

Figure 2 is a top view of the same.

Figure 2 is a detail view in front elevation, partly in section through the alley, showing the target and the indicator and register.

Figure 4 is a view in side elevation, on a larger scale than that of Figures 1, 2 and 3, of the registering and indicating mechanism and the parts immediately associated therewith.

Figure 5 is a view in front elevation of the parts shown in Figure 4.

Figure 6 is a detail view in side elevation of the coin-controlled releasing and resetting lever and some associated parts.

Figure 7 is a top view of some of the parts shown in Figure 6.

Figure 8 is a view partly in side elevation and partly in longitudinal section illustrating particularly the ball releasing devices.

Figure 9 is a top view of the parts shown in Figure 8.

The form of alley in which the several features of the invention are shown as embodied, is sufficiently indicated in Figures 1 and 2, the position of the player being indicated at *a* and the position of the target at *a'*. The floor of the alley on which the balls are rolled, as indicated at *a''*, is preferably inclined so that the balls are rolled by the player up hill from the player's stand *a* toward the target *a'*. At one side of the floor *a''* is a trough *a'''*, into which the balls are delivered from the target and by which the balls are returned by gravity to the player's stand, the trough being inclined as indicated.

In connection with the return trough *a'''* and preferably located near the target, is a ball retaining and releasing device *b*, shown in Figures 1, 2, 8 and 9, which is adapted to retain the balls delivered from the target and scoring mechanism and to release a determinate number when operated. As shown, a bar *b'*, pivoted on a horizontal axis *b''* below the trough *a'''* and counter weighted, as at *b'''*, carries at one end a stop *b''''* which is provided with an extended finger *b'''''* and at the other end with a yieldingly mounted stop *b''''''*. Below the lever *b'* is mounted a second lever *b'* which is connected to the wires *d'*, *d''* hereinafter mentioned. When the lever *b'* is moved by a pull on the wire *d'* it causes the lever *b'* to move from the position shown by full lines into the position indicated by broken lines, moving the stop *b''''* into the path of the balls and moving the stop *b''''''* out of the path of the balls. The balls which are thus released immediately begin to roll down the trough and, rolling over the extended portion *b''''*, which then lies in the slotted bottom of the trough, hold the lever *b'* in its releasing position. As soon as the last of the balls has rolled from the extension *b''''* the lever *b'*, under the influence of the weights *b''''*, returns to its normal position, to permit the determinate number of balls to move into position to be released.

The lever b' is conveniently operated by the operation of a lever d at the player's position, being connected thereto as by a wire d' , while a wire d^2 , also connected to the lever b' , forms an extension of the wire d' for the operation of the indicator resetting devices. The lever d is preferably coin-controlled by any suitable devices. Such devices in detail do not form part of the present invention. The devices illustrated in Figures 6 and 7 of the drawings may be briefly described as follows:

At the target end of the alley there is erected a suitable housing e which may comprise side plates e' and suitable frame members, as at e^2 . Between the side plates e' may be hung at their upper ends, upon a cross rod f , pins or flat silhouettes of pins f' which have different values. In the embodiment of the invention illustrated the middle pin is assumed to have a value of thirty, each of the two adjacent pins, one at each side of the middle pin, is assumed to have a value of twenty, and each of the outside pins is assumed to have a value of ten. The spaces occupied by the several pins are marked off by tapered partitions f^2 , so that each ball, as it is delivered at the target, shall be guided into one space or another and shall not strike two pins simultaneously. The partitions are continued beyond the end of the alley and deliver the balls into a common transverse trough f^3 , inclined to one side, so that all of the balls, wherever they strike the target, are eventually delivered to the return trough a^3 . In the spaces beyond the pins f^2 are hung fingers g , g' , g^2 , g^3 , g^4 adapted severally to be moved by the balls as they pass from the end of the alley. The finger g stands behind the middle pin, is moved by a ball which has struck the middle pin and is adapted, as hereinafter explained, to advance the scoring mechanism through an extent of movement which corresponds to thirty. The two fingers g' and g^2 stand behind the pins adjacent to the middle pin, one on each side, and as these two pins have the same value and the scoring mechanism is advanced to a corresponding extent whether the ball strikes one or the other of the fingers g' , g^2 , these two fingers g' and g^2 are connected so as to move together, as by a bar g^5 , while the two fingers g^3 and g^4 , standing behind the outside pins which have each a value of ten, are connected together as by a bar g^6 . All of the fingers g , g' , g^2 , g^3 , g^4 , are hung for free movement upon a rod g^7 and also hung for free movement upon the same rod is a bail g^8 , the bar g^6 of which stands just back of all of the fingers so that the bail is moved by the movement of any one of the fingers. The bail g^8 has an arm g^{10} which is connected by a wire g^{10x} to the scoring mechanism so that at each movement of the finger g the scoring mechanism is ad-

vanced through an extent corresponding to the value thirty of the middle pin. The bail g^8 is moved whenever any of the pins g' , g^2 , g^3 , g^4 is moved, but the movement of the fingers g' , g^2 , g^3 , g^4 limits the movement of the scoring mechanism as will be described, the two fingers g' and g^2 having, on the hub of the finger g^2 , an arm g^{11} which is connected by a wire g^{11x} to the scoring mechanism in such manner as to limit the movement of the scoring mechanism to the value of twenty, while the fingers g^3 and g^4 have, on the hub of the finger g^4 , an arm g^{12} , which is connected to the scoring mechanism by a wire g^{12x} in such manner as to limit the movement of the scoring mechanism to the value of ten.

The indicator and register of the scoring mechanism comprises a series of plates h which bear on one face the corresponding indication of value, the first plate of the series, which is shown in Figures 4 and 5 as exposed, having the figure 0 on its face, while the successive plates bear on their faces the numerals 10, 20, 30, etc. The plates h are pivotally hung between the side plates h' of a carrier which is mounted on an axis h^2 and is adapted to be moved upon its axis, as hereinafter described, through the movement of the fingers g , g' , etc., so as to cause one, two or three of the indicator plates to be moved into exposed position. When the carrier is in its initial position, to which it is restored by the resetting mechanism to be described, the zero plate h has its face exposed to view, as shown in Figure 5, while the other plates of the series are either in the position shown at the right hand of Figure 4 or in the position shown at the left hand of Figure 4, these plates last referred to being held by a pivoted detent h^8 which is supported by an arm h^4 . If the carrier h' is advanced through one step only, from the position shown in Figure 4, then the next plate h which is the "10" plate alone is released, this movement being effected when a ball strikes the pin g^3 or the pin g^4 . If, however, the first ball strikes the finger g , then the carrier is advanced through three steps, which movement is sufficient to release three plates h from the detent h^8 , thereby exposing the plate "30" to view. In whatever position the carrier h' may be, it is actuated so as to expose the third successive indicator plate whenever the finger g is hit by a ball; its movement, initiated by the movement of the bail g^8 , is limited so as to expose the second successive plate whenever either finger g' or g^2 is hit by a ball; and its movement, also initiated by the movement of the bail g^8 , is limited so as to expose the next successive plate whenever either finger g^3 or g^4 is struck by a ball.

The carrier h' is over-balanced so that it tends always to move in a counter-clockwise

direction as seen in Figure 4 and it is provided, near the margin of one side plate, with a series of escapement holes h^s which are so spaced apart as to permit the movement of the carrier sufficient to release the next successive indicator plate or the second or the third, as the case may be. These holes are adapted to be engaged by escapement pins i and i' respectively, the pin i' normally engaging the carrier to prevent movement thereof but movable out of engagement with the carrier and movable into engagement therewith and also movable with the carrier to a variable extent as determined by the finger g' , g^2 , g^3 or g^4 which is struck by the ball. The pin i is carried by an arm i^2 of a right angled lever i^2 i^3 , which is pivoted on the frame, as at i^4 and is held normally by a spring i^5 in the position shown in Figure 5. The arm g^{10} is connected by the wire g^{10x} to the arm i^3 and the latter is also connected by a link i^6 with an arm i^7 which projects from a slotted link i^8 which is pivoted as at i^9 so as to swing toward and from the carrier, and receives between its members and between pins i^{10} which limit its maximum movement, the loosely pivoted bar i^{11} which carries the escapement pin i' . The bar i^{11} is counter-weighted, as at i^{12} , so that it stands normally in the relative position shown in Figure 4, and is capable not only of swinging in a horizontal direction, so as to engage the pin i' with the carrier, but of swinging in a vertical direction to an extent limited, at the maximum, by the pins i^{10} . It will now be understood that at every actuation of the finger g , the pin i is disengaged from the carrier and the pin i' is simultaneously engaged therewith, whereby the carrier is permitted to move under the influence of gravity through an extent limited by the coaction of the pins i^{10} with the bar i^{11} , such movement being sufficient to permit the release of three successive plates so that the face of the third successive plate is exposed to view from the front. The arm g^{11} , which moves with the fingers g' , g^2 , is connected by the wire g^{11x} to a spring pressed lever k which underlies an arm k' of a latch k^2 , pivoted on the axis i^9 and having a stop k^3 which normally stands out of the path of movement of the escapement bar i^{11} so that the carrier may move through two steps only. In like manner, the arm g^{12} is connected by the wire g^{12x} with a counter-balanced lever l which coacts with the arm l' of a latch l^2 having a stop l^3 normally out of the path of the escapement bar i^{11} but permitted by movement of the lever l , to swing into the path of the escapement bar i^{11} and limit the movement thereof so that the carrier may move through one space only and therefore expose the next successive number plate.

It will now be understood that the indicator carrier is released at every operation of any of the fingers g , g' , g^2 , g^3 , g^4 , that when it is released by movement of the middle finger g it is permitted to have its maximum movement so as to release three successive number plates, that when it is released by the movement of either finger g' , g^2 , it is permitted to have movement sufficient to release two successive number plates, and that when it is released by movement of either finger g^3 , g^4 it is permitted to have movement sufficient to release only one number plate.

At the end of a game or of a string of 80 balls it is necessary to restore the carrier h , with its indicator plates, to the position shown in Figure 4. For this purpose the wire d^2 , connected by the wire d' to the resetting lever d , is connected to a spring 85 pressed lever m , m' , m^2 shown in Figures 1 and 2, the arm m^2 being connected, as by a chain m^3 , to the hub of a resetting lever m^4 which is mounted on the axis of the carrier and is adapted to contact with a pin h^s 90 which projects from the adjacent side plate of the carrier and thereby to restore the carrier to its initial position. The lever m^4 is extended and provided with a projecting arm m^5 which also contacts with the zero 95 indicating plate h and through it raises all of the other indicating plates which have been released above the swinging detent h^s so that they shall be held thereby as shown in Figure 4. A fixed stop m^6 is provided 100 to limit the movement of the resetting lever.

It will now be understood that when the parts are in the positions shown in Figures 1 and 4 and the lever d has been released by the insertion of a coin, the operation of 105 the lever releases a determinate number of balls and permits them to roll to the player's end. The scoring mechanism is shown in Figure 4 as in its initial position, but ordinarily it will be left by the preceding player 110 in a more or less advanced position, so that the operation of the lever d effects the restoration of the scoring mechanism to initial position as well as the release of the balls. The player now rolls the balls in succession 115 toward the target, each ball effecting the automatic advance of the scoring mechanism through an extent which corresponds to the value of the pin struck. Thereby the valve of the pin struck is indicated by the 120 difference in values of the last two plates exposed and at the same time the total of the score is registered.

It will be understood that various changes in details of construction can be made to suit the convenience of the manufacturer or the requirements of use and that the invention, except as pointed out in the claims, is not limited to the particular construction shown and described herein.

I claim as my invention:

1. In a bowling game apparatus, the combination of a scoring mechanism, several devices in different positions adapted to be actuated by the balls, a single means actuated by all of said devices to initiate movement of the scoring mechanism, and other means actuated by certain of said devices to limit in different degree the movement 10 of the scoring mechanism.
2. In a bowling game apparatus, the combination of a scoring mechanism, several devices in different positions adapted to be actuated by the balls, a single escapement 15 for the scoring mechanism, means actuated by all of said devices to operate the escapement and other means actuated by certain of said devices to limit in different degree the movement of the scoring mechanism.
3. In a bowling game apparatus, the combination of a scoring mechanism, movable fingers mounted in different positions to be struck by the balls, a single means actuated by all of said fingers to initiate the movement 25 of the scoring mechanism and other means actuated by certain of said fingers to limit in different degree the movement of the scoring mechanism.
4. In a bowling game apparatus, the combination of a scoring mechanism having a tendency to forward movement, a single escapement for said scoring mechanism, several fingers in different positions to be struck by the balls, other means actuated by 30 all of said fingers to operate the escapement, and means actuated by certain of said fingers to limit in different degree the movement of the scoring mechanism.
5. In a bowling game apparatus, the combination of a scoring mechanism having a tendency to forward movement, a single escapement for said scoring mechanism, several fingers in different positions to be struck by the balls, means actuated by the 35 movement of said fingers to operate the escapement, other means operated by certain of said fingers to limit the movement of the scoring mechanism, and other means actuated by the movement of other of said fingers to limit in different degree the movement 40 of the scoring mechanism.
6. In a bowling game apparatus, the combination of a scoring mechanism comprising an over-balanced movable carrier having a tendency for forward movement and successive number plates mounted movably on the carrier, a relatively fixed detent for the number plates, and means to initiate the forward movement of the carrier whereby successive number plates are exposed 45 to view.
7. A scoring mechanism for bowling game apparatus, etc., comprising an over-balanced carrier mounted to swing upon an axis, and having a tendency for forward movement 50
8. A scoring mechanism for bowling game apparatus, etc., comprising a carrier mounted to swing upon an axis, and having a tendency for forward movement, number plates mounted on the carrier, an escapement cooperating with the carrier, means to operate the escapement, and means to limit the movement 55 of the carrier.
9. A scoring mechanism for bowling game apparatus, etc., comprising a carrier mounted to swing upon an axis, and having a tendency for forward movement, number plates mounted on the carrier, an escapement for cooperation with the carrier and including a bar movable into and out of engagement with the carrier and movable with the carrier, means to operate the escapement and means to limit the movement 60 of said bar.
10. A scoring mechanism for bowling game apparatus, etc., comprising a carrier mounted to swing upon an axis, and having a tendency for forward movement, number plates mounted on the carrier, an escapement for cooperation with the carrier and including a bar movable into and out of engagement with the carrier and movable 65 with the carrier, means to operate the escapement, a stop movable into the path of said bar and means to control the movement of said stop.
11. A scoring mechanism for a bowling game apparatus, etc., comprising a carrier mounted to swing upon an axis and having a tendency for forward movement, number plates mounted on the carrier, an escapement for the carrier comprising a pin movable 70 into engagement with the carrier to hold the carrier from movement and movable out of engagement with the carrier, and a second pin movable into and out of engagement with the carrier and movable with the carrier, means to limit the movement of the last named pin, and means to move said pins in alternation into and out of engagement with the carrier.
12. A scoring mechanism for a bowling game apparatus, etc., comprising a carrier mounted to swing upon an axis and having a tendency for forward movement, number plates mounted on the carrier, an escapement for the carrier comprising a pin movable 75 into engagement with the carrier to hold the carrier from movement and movable out of engagement with the carrier, and a second pin movable into and out of engagement with the carrier and movable 80

with the carrier, means to limit the movement of the last named pin, means to move said pins in alternation into and out of engagement with the carrier, a stop to limit 5 the movement of the second named pin and means to move said stop into and out of operative position.

13. A scoring mechanism for a bowling game apparatus, etc., comprising a carrier 10 mounted to swing upon an axis and having a tendency for forward movement, number plates mounted on the carrier, an escape- 15 ment for the carrier comprising a pin movable into engagement with the carrier to hold the carrier from movement and movable out of engagement with the carrier, and a second pin movable into and out of engagement with the carrier and movable with the carrier, means to limit the movement of 20 the last named pin, means to move said pins in alternation into and out of engagement with the carrier, stops to limit in different degree the movement of the last named pin, and means to move said stops into and out 25 of operative position.

14. A scoring mechanism for bowling game apparatus, etc., comprising a carrier mounted to swing upon an axis, successive 30 number plates mounted upon the carrier, a lever mounted on a fixed pivot and having a pin for engagement with the carrier, a bar having a second pin for engagement 35 with the carrier and mounted for movement toward and from the carrier and with the carrier, a slotted lever engaging said bar to move the bar toward and from the carrier and to permit movement of the pin with the carrier, and means to actuate said levers to move the pins in alternation into and out 40 of engagement with the carrier.

15. A scoring mechanism for bowling

game apparatus, etc., comprising a movable carrier and number plates mounted thereon, a series of fingers mounted in different positions to be struck by the balls, a bail adapted 45 to be moved by the movement of any of said fingers and operatively connected to the carrier to initiate the movement thereof, and means actuated by the movement of certain of said fingers to limit in different degree 50 the movement of the carrier.

16. A scoring mechanism for bowling game apparatus, etc., comprising a movable carrier and number plates mounted thereon, a series of fingers mounted in different positions to be struck by the balls, a bail adapted 55 to be moved by the movement of any of said fingers and operatively connected to the carrier to initiate the movement thereof, means actuated by certain of said fingers to limit 60 the movement of the carrier, and means actuated by other of said fingers to limit in different degree the movement of the carrier.

17. A scoring mechanism for bowling 65 game apparatus, etc., comprising a movable carrier and number plates mounted thereon, a series of fingers mounted in different positions upon a common axis to be struck by the balls, a bail adapted to be moved by the 70 movement of any of said fingers, means actuated by the movement of the bail to initiate the movement of the carrier, the fingers being connected in pairs on opposite sides of the middle finger, and means actuated 75 by the movement of the pairs of fingers on opposite sides of the middle finger to limit the movement of the carrier.

This specification signed this 23d day of May, A. D. 1922.

CHRIST PAPOUCHIS.
